AUTOMATIC TRAIN-STOPPING DEVICE.

1,192,087.

specification of Letters Patent.

Patented July 25, 1916.

Application filed May 8, 1914. Serial No. 837,141.

To all whom it may concern:

Be it known that I, JESSE MARCROFT, a citizen of the United States, residing at Cranston, in the county of Providence and State of Rhode Island, have invented certain new and useful Improvements in Automatic Train-Stopping Devices, of which the following is a specification.

My invention relates to safety stopping devices for railroad trains and consists of certain improvements in the arrangement and method of operation of the same.

My improvements relate particularly to a type of apparatus such as that shown in my pending application for patent, Serial No. 765,638, filed May 5, 1913, the object being to increase the efficiency and extend the range of adaptability of the device.

The particular object of the invention is to provide an automatically-operated mechanism for shutting off the locomotive power and applying the brakes whenever a danger signal is set against the train.

A further object of my improvement is to adapt the device to regulate the speed of the train to require a reduction therein under danger conditions and to prevent excessive speed under normal conditions.

The manner and means for carrying out the improvement are fully described in the following specification, illustrated by the accompanying drawing, in which like reference characters designate like parts.

The single sheet of drawing shows a portion of the main operating mechanism of a usual type of steam locomotive and illustrates my invention as applied thereto.

While I have preferred to herein illustrate and describe my device in connection with a steam locomotive and arranged to be operated by steam pressure, it is to be understood that other kinds of fluid pressure such as air could be employed without materially changing the arrangement of the mechanism. For this reason my invention is equally well adapted for electrical locomotives or for other types of self-propelled engines.

Referring to the drawing, B designates the main feed or supply-pipe of a locomotive which connects the steam-dome, not here shown, with the driving cylinders.

Steam is admitted to the pipe B through two opposite ports b, b which are adapted to be closed by a double throttle-valve C of the puppet type. The valve C is operated by a stem c connected to bell-crank-lever c' which

is controlled by a rod c''. The rod c'' runs to the cab of the engine and is connected with the usual engineer's throttle-lever, not here shown.

Between the throttle-valve C and the cylinders is an auxiliary valve E adapted to close the pipe B to prevent steam reaching the cylinders when the valve C is open. The valve E serves as a means for stopping the engine under danger conditions and is adapted to be operated automatically from the controlling-mechanism of the device as later explained. The valve E may be of any usual construction and as here illustrated is of the "butterfly" type having a pivoted blade e arranged to swing across the opening in the pipe B. A weighted arm e' secured to the end of the pivot e of the blade e acts to normally close the valve through the effect of gravity, and a second arm e'' is employed to control its position positively from the operating mechanism of the device. Connected to the end of the arm e'' by a pin-and-slot arrangement shown at e''' is a horizontal rod F adapted to slide in the fixed bearings f, f'. The opposite end of the rod F is connected to the lever g of a relief-valve G which forms part of the air-brake system of the train. Suitable means are provided for regulating the range of movement of the valve-lever g under action of the rod F, but these are not herein shown and described as they are not essential to the main operating elements of the invention. Suffice it to state that movement of the rod F in the direction indicated by the arrow x in the drawing, which acts to close the auxiliary-valve E and shut off steam from the cylinders, also operates to open the air-valve G to effect the application of the brakes of the train in the usual manner.

Engaging the rod F through a pin-and-slot connection shown at h is a bell-crank-lever H which is pivoted on a stud h' secured in a suitable bracket or support not here shown. The other arm h'' of the lever H carries a connecting-rod I which is pivotally connected to the end of the rod j of a piston J. The piston J is adapted to slide in a cylinder K and is actuated by pressure admitted through suitable valve-ports at one side of the cylinder. As here shown the piston J is operated by steam pressure admitted to the cylinder K through the valve-chamber or steam-chest L which latter is connected to the main supply-pipe B of the engine by a relatively small feed-

pipe l . The pipe l is tapped into the end of the main pipe B at b' adjacent the throttle-valve C so that whenever the latter is open pressure will be admitted to the steam-chest L . In the steam-chest L is a sliding valve M of the "balanced" type. Leading from the steam-chest L into the upper end of the cylinder is a port k and at the bottom of the cylinder is a second intercommunicating port k' . A third port k^2 leads from the center of the steam-chest L through a duct k^3 to the upper end of the cylinder K . Steam supplied through the pipe l enters the steam-chest L through a double port l', l^2 . Two exhaust ports l^3 and l^4 at the upper and lower ends of the steam-chest are provided with pipes l^5 , l^6 communicating with the atmosphere. The valve M is formed with a plurality of seats m , m' , m^2 and m^3 adapted to open and close the various ports of the steam-chest L as it slides therein. The valve M is controlled by an electric magnet M' energized from a normally-closed circuit as later described. Preferably, the magnet M' is of the solenoid type and the valve-stem m^4 acts as a sliding armature therefor. The upper portion of the valve-stem m^4 is reduced in diameter and slides in a bearing formed by the end plate m^5 of the magnet M' . At its end it carries a beveled detent or lock-piece m^6 adapted to coact with a pawl or latch n pivoted on a collar N which is fixedly secured to the rod F . The latch n is adapted to slide across the top of the lock-piece m^6 when the rod F is moved in the direction opposite to that indicated by the arrow x , and drops down behind the detent m^6 through the action of gravity. A pin n' on the collar N then holds the latch n from further rearward movement so that when it engages the edge of the detent m^6 the rod F is restrained from movement in the direction indicated by the arrow x , and hence the auxiliary steam-valve E will normally be maintained in open position. When the magnet M' is deenergized the valve-stem m^4 is released and moves downward through the action of gravity. Under this condition the detent m^6 will be released from the pawl n and the weighted arm e' will act to close the valve E .

To accelerate the closing of the valve E and render its action positive, the piston J acts through the bell-crank-lever H to slide the rod F to the left when steam is admitted to the upper end of the cylinder K . Normally, with the valve L held in its raised position by the magnet M' the port k^2 which admits steam to the upper end of the cylinder K will be closed by the valve-seat m^2 . On the other hand, the port k' communicating with the lower end of the cylinder K will be open so that pressure will be exerted on the bottom of the piston J tend-

ing to hold it at the upper end of the cylinder, a suitable stop j' being provided to limit the movement of the piston in this direction. As the steam enters the valve-chamber or steam-chest L through the double ports l', l^2 it exerts an equal pressure on the opposite sides of the valve-seat m^2 and hence there is no tendency for the valve M to be moved against the action of the magnet M' . With the valve M in its normal, balanced position the seat m will be raised to open the exhaust port l^3 while the port l^4 will be closed by the seat m^3 .

The circuit for normally maintaining the magnet energized and the means for interrupting the same to deenergize the magnet to cause it to release the armature m^4 will next be described.

The current for the magnet M' may be supplied from any suitable source of electrical energy such as a generator or storage battery. As here shown one lead of the solenoid M' is connected to one pole of a battery O by a wire o . From the other pole of the battery O a wire o' leads to the terminal p of a normally-closed switch P . A wire p' leading from the other terminal p^2 of the switch P is grounded at p^3 in the metal framework of the engine. The wire o' also leads to the terminal r of a second switch R and connected with the opposite terminal r' thereof is a wire r^2 which connects with a wire r^3 leading from the magnet M' . With the switch R closed, as illustrated in the drawing, a complete circuit is established between the battery O and magnet M' through the wires o , o' , switch R and wires r^2 , r^3 so that the magnet remains normally energized. The wire r^3 which leads from the magnet M' in the above described circuit, is continued beyond the switch R and forms a part of a branch or shunt circuit which includes the contact-mechanism adapted to coöperate with the signal system. The arrangement of this part of the apparatus is as follows:

Mounted on the locomotive in any convenient location is an arm or bracket S which carries the contact-device S' . This latter consists preferably of a pivoted arm s at the end of which is a metal shoe s' . Adjacent the arm s is a switch T adapted to be operated therefrom. The switch T is preferably of the "knife" type having a pivoted blade t adapted to make contact with the terminal t' . The opposite end of the blade t is connected by a link t^2 with the end of the arm s to be moved thereby. Normally, a spring t^3 tends to maintain the switch T closed, but when the outer end of the arm s is depressed, as shown in the drawing, the blade t will be carried away from the terminal t' to open the switch. The arm s is operated through contact of its shoe s' with a rail U which runs along

side the main tracks U' , U'' . Preferably, the contact-rail U is of the inverted type formed with a concave, lower surface adapted to fit over the upper, rounded face of the shoe s' . This form of rail is designed particularly to shed moisture and to prevent it from freezing on the contact surface. As a further precaution I have illustrated the rail U as also provided with protecting 10 shed-like strips u , u extending along its sides. It will also be understood that the contact-rail has upwardly inclined ends, not here illustrated, under which the shoe s' rides in entering into contact with the main 15 portion of the rail by which it is depressed. The contact-shoe s' is wired into the main circuit as follows: The wire r^3 leads past the switch R as before described and is carried down along the bracket S with its end 20 grounded at r^4 in the metal shoe s' . Another wire r^5 , also grounded in the shoe s' , leads to the switch-blade t , and from the switch-terminal t' a wire r^6 is grounded at r^7 in some metal part of the engine. It will 25 therefore be seen that with the switch-blade t closed, the circuit connecting the magnet M' and battery O will be completed through the wire r^3 , shoe s' , wire r^6 , switch T , wire r^7 , grounds r^7 , p^3 , switch P and wire o' , this 30 circuit being auxiliary to the main circuit first described. A still further continuation or branch of the circuit comprises connections through the contact-rail U and service-rail U' and is opened or closed through 35 the operation of the signal-system as next described.

It is to be understood that the contact-rail U is located adjacent the signal-stand which controls any one block in the line. 40 That is to say, it can be used in conjunction with either the "distant" signal or "home" signal, or with both. Referring again to the drawing, I have here shown a portion of a usual form of signal-mast V on which 45 is pivoted the common type of semaphore-arm V' . The arm V' is controlled by a vertical rod v and as here illustrated is set in a horizontal position indicating "danger." Mounted on the signal-stand or 50 mast V is a switch box v' inclosing a "knife" type of switch V^2 comprising the blade v^2 and terminals v^3 , v^4 . The end of the switch-blade v^2 is connected to the rod v to be operated therefrom and with the signal set 55 at "danger", as here shown, the switch will be open. When the arm V' drops to "clear" position it will act through the rod v to close the switch. One terminal v^3 of the switch V^2 is connected by a wire v^5 to the 60 contact-rail U , while the other terminal v^4 is connected by a wire v^6 to the service-rail U' . The wire v^6 being grounded in the rail U' will also ground through the wheels u^2 to the other metal parts of the engine. 65 With the switch T of the first-described,

shunt circuit open the current will still flow through a circuit comprising the wire r^3 , contact-shoe s' , rail U , wire v^6 , switch V^2 , wire r^6 , rail U' , thence through the wheels u^2 and metal of the engine, ground p^3 and wire o' , and thereby connecting the magnet M' with the battery O . 70

The switches P and R in the main circuit first described are provided for the purpose of interrupting the circuit to operate the 75 stopping-mechanism under different speed conditions. That is to say, these two switches are actuated from an automatic governor-device applied to any going part of the engine or train. A simple and convenient mechanism for this purpose is here 80 illustrated as consisting of a usual type of "ball" governor Y attached to the locomotive axle u^3 . Secured to the axle u^3 is a collar y on which are pivoted two arms y' , y' carrying ball-weights y^2 , y^2 at their ends. A collar y^3 slidably mounted on the axle u^3 is connected to the arms y' , y' by the links y^4 , y^4 . A collar y^5 fast on the axle u^3 serves 85 as a bearing for the end of a spring y^6 which presses against the collar y^3 and tends to normally prevent the outward movement of the governor-arms y' , y' . Pivoted on the truck or frame of the locomotive is an arm or lever Z , the end of which straddles the 90 collar y^3 and engages trunnions y^7 carried by a sleeve y^8 mounted to turn on the collar y^3 . The lever Z is connected to a sliding rod z which acts to operate the switches P and R . Preferably, these latter are of the 95 "knife" type having blades p^4 and r^8 formed with right-angled arms p^5 and r^9 reaching down adjacent the rod z . Suitable springs z' , z' connect the arms p^5 and r^9 to a pin or other fastening device z^0 and tend to normally maintain the switch P closed and the switch R open. Adjustably secured to the rod z are two collars z^4 and z^5 adapted to engage the switch-arms p^5 , r^9 to control the 100 position of the blades p^4 and r^8 . When the engine is at rest the governor-arms y' , y' will be in their retracted position as shown in the drawing and the lever Z will hold the collar z^5 against the switch-arm r^9 to maintain the switch R closed. When the 105 engine is started and reaches a predetermined speed the governor Y will operate to move the lever Z to slide the rod z and carry the collar z^5 away from the arm r^9 to allow the switch R to be opened under the action of its spring. The switch R is provided for 110 limiting the speed of the train under "danger" conditions and the collar z^5 is adjusted to allow its automatic opening under a minimum speed of about ten miles an hour or less. The purpose of the switch P is to limit the maximum rate of speed of the train under all conditions. By setting the collar z^4 so that it will knock off the switch 115 when the train attains a speed of say sixty 120

5 miles an hour the main circuit of the electrical devices is broken and the automatic stopping-mechanism will be set in operation as more fully explained hereinafter. It is
 10 to be understood that I have here illustrated my new device in its simplest form with the electrical connections shown more or less diagrammatically in the drawing. In practice certain modifications and refinements
 15 would be made in the mechanism, but since these are not necessary to an understanding of the invention I have not gone into the matter in detail.

The method of operation of the complete device is as follows: With the locomotive or engine at rest both switches P and R will be closed and the current from the battery O will flow through the circuit comprising the wiring o' , r^2 and r^3 to energize 20 the magnet or solenoid M'. The latter will therefore normally maintain the armature m^4 in its raised position with the detent m^8 set against the latch n to prevent the rod F from sliding to the left. In this manner 25 the valve E is maintained in its open position against the action of its weighted arm e' and the air-brake valve G is also held closed by the lever g. When the throttle-valve C is opened to admit steam to the 30 driving cylinders through the supply-pipe B, the engine will start to operate and pressure will also be admitted to the steam-chest L through the small pipe l. Steam entering the steam-chest L through the 35 double ports l' , l^2 will exert equal pressure on both sides of the valve-seat m^2 without influencing the "balanced" valve M to be moved against the attraction of the solenoid M' for the armature m^4 , and hence the port 40 k' will remain normally open. This allows steam to enter the cylinder K at the lower end thereof and therefore pressure will be applied to the under side of the piston J tending to maintain it in its raised position, 45 as shown in the drawing. Now, as the engine starts to move and gains speed the arms y' , y^2 of the governor-device Y will separate, under influence of centrifugal force, and the collar y^3 will be slid to the left to 50 swing the lever Z in the same direction. This acts to slide the rod z to carry the collar z^5 away from the switch-arm r^9 and hence the switch R will be opened to break the circuit at this point. As before mentioned, the collar z^5 is adjusted to release the 55 switch-arm r^9 when the train reaches a predetermined speed at which it is considered safe to run under danger conditions. The opening of the switch R does not of itself 60 cause the interruption of the electrical circuit, however, it being necessary that the circuit through the contact-device S' be also broken. Normally, with the train running on an open track the contact-arm s will remain in its raised position with the switch 65

T closed. Under these conditions the electrical circuit will be completed from the wire r^3 leading from the magnet M', through the metal shoe s' to the wire r^5 and thence back through the closed switch T and wire r^6 to the ground r^7 . From the ground r^7 the circuit continues through the ground p^8 , wire p' , switch P and wire o' to the battery O, and thence through the wire o back to the magnet M'.
 75

As before explained, the contact-rails U are placed adjacent the "distant" signals and within the blocks protected thereby. Now, as the train enters a block, if the signal is set to indicate a "clear" track, with the 80 semaphore-arm V' lowered, the switch V² on the signal-mast V will be closed. Under these conditions, when the contact-shoe s' comes into engagement with the inclined end of the contact-rail U and is depressed thereby, then the switch T will be opened, but the circuit will still be closed through the switch V². That is to say, the opening of the switch T does not act to interrupt the circuit unless the switch V² is open. With 90 the switch V² closed the current will flow from the wire r^3 through the shunt circuit comprising the wire v^5 , terminal v^8 , switch-blade v^2 , terminal v^4 , and wire v^6 to the service-rail U'. The contact of the truck-wheels u^2 with the rail U' grounds the circuit in the frame of the locomotive from 95 which it is completed through the ground p^8 and switch P as before described.

The working of the apparatus under normal conditions having now been described, its method of operation under danger conditions will next be explained: When a signal is set against the train to indicate "danger," or in some cases to call for caution in proceeding, the semaphore-arm V' will be raised as shown in the drawing and the switch V² will be opened to interrupt the circuit at this point. Now, if the engineer fails to observe the signal and enters the 100 "block" without slowing down enough to automatically close the switch R, the device will operate to stop the train in the following manner: As the train enters the "block" the contact-shoe rides along the rail U and 105 is depressed to open the switch T as before described. The circuit is therefore interrupted at this point and since the switch V² has been opened by the operation of the semaphore V' the current cannot flow through the 110 shunt circuit comprising the wires v^5 and v^6 which connect the rail U with the rail U'. It will therefore be seen that the circuit connecting the battery O with the magnet M' will be interrupted and hence the magnet 115 M' will be immediately deenergized. This will cause the armature m^4 to be released and the valve M, which is relatively heavy, will slide downwardly through the action of 120 gravity. As the valve M moves down in 125 130

the steam-chest L the entrance port l^2 will be closed, thereby causing pressure on the upper side of the valve-seat m^2 to accelerate the movement of the valve. At the same time the inlet port k^2 will be opened to admit steam to the upper end of the cylinder K while the upper outlet ports k and l^3 will be closed by the valve-seat m . Meanwhile, the outlet port l^4 at the bottom of the steam-chest L will be opened to exhaust the pressure from the cylinder through the lower port k' . It will be understood that the first slight movement of the valve M under the action of gravity frees the detent m^6 from the latch n to release the rod F. As soon as the rod F is free to slide, the weighted arm e' on the valve E will act to close the latter to shut off the steam from the driving cylinders and the lever g on the air-valve G will also be turned to exhaust the air-pressure and effect the application of the brakes. To make the device more positive, however, it is adapted to effect the movement of the rod F from steam-pressure in the cylinder K. That is to say, as soon as the armature m^4 is released by the magnet M', the valve M opens the port k^2 and steam enters therethrough to the upper end of the cylinder K through the duct k^3 . This causes pressure on the upper side of the piston J to force the latter downwardly and through its rod j and connection I the bell-crank-lever H is rocked to slide the rod F in the direction indicated by the arrow x. In this way the valve E is actuated positively to shut off the power from the engine and the brakes are simultaneously applied to effect a relatively quick stop.

After the train has been brought to a full stop the governor-device Y will cease to hold the switch R open and hence the current will again return to the magnet M'. As soon as the magnet M' becomes energized again it will raise the valve M and steam will be once more admitted to the bottom of the cylinder K through the port k' . This pressure acts to raise the piston J to slide the rod F to the right and the valve E will again be opened and the air-valve G closed. As the rod F is carried to its retracted position, the latch n rides over the detent m^6 and again locks the parts of the device in operative relation, as before described. Now, if the engineer wishes to proceed with caution, that is, at a slow rate of speed, to determine what the danger condition may be, he can do so as follows: By opening his throttle to a limited extent steam is admitted to the cylinders to drive the engine up to a speed within the predetermined limit. In other words, the engineer may proceed at a slow rate of speed without causing the governor-device Y to open the switch R so that the magnet M' will remain energized to prevent the operation of the stopping-device even though the signal-switch V² remains open. Should he attempt to run faster than this "legal" or prescribed speed, however, while the signal V' is still set against the train, then the switch R will be opened and the automatic stopping-device will act to stop the train again as previously explained.

The purpose of the switch P, as before indicated, is to prevent the engineer from running his train at excessive speed. The collar z⁴ on the rod z of the governor-device is adjusted to knock off the switch-blade p⁴ whenever the train exceeds the legal or prescribed maximum rate of speed at which the engineer is allowed to run. Whenever this occurs, the main electrical circuit is interrupted at the switch P and this will cause the magnet M' to be deenergized to operate the stopping-device as previously explained.

It will be seen that my new device provides a very simple yet positive means for stopping the train under any and all conditions of danger. One particular advantage of the apparatus lies in the fact that it is entirely beyond the control of the engineer so that its automatic action cannot be hindered or prevented in any possible manner. At the same time its method of operation is such that it does not hold the locomotive "dead" when a signal is set against the train, but allows the engineer to proceed cautiously to determine the danger. In addition it also acts to prevent excessive speed of the train and therefore serves to avoid accidents from this cause.

In the apparatus of my previous application, before referred to, the automatic stopping-mechanism is controlled by a normally open electric circuit, and it will be obvious that the present device might be arranged to be operated in the same way. It has been determined, however, that a normally closed circuit is preferable for the following reasons: In the first place, should any of the electrical mechanism become deranged or disconnected notice of the trouble would immediately be given by the stopping of the trains. For this reason the device cannot get out of order and be rendered inoperative without knowledge on the part of the engineer, so that it can be said that it acts as its own sentinel. Furthermore, the parts are arranged to act through gravity even if the steam pressure were to fail and therefore it cannot become inoperative from this cause. For instance, if the engineer should willfully attempt to run past a danger signal by shutting off his power and allowing his train to "coast", this would not prevent the controlling-mechanism from acting through gravity and hence the brakes would be applied and the train brought to a stop. It is believed that

every possible contingency of this sort is provided for by my new improvements and therefore the apparatus can be said to be absolutely positive in action and thoroughly reliable under all conditions. It can be applied to practically any type of steam locomotive now in use and can also be adapted for electrical locomotives by arranging it to be operated by air pressure. It is also called to attention that my new stopping-device might be operated independently of the signal system. That is to say, the electrical circuit could be controlled by switches located at the signal-towers or despatching stations or used in connection with cross-overs or track-switches.

Various other modifications might be made in the form and arrangement of the new device without departing from the spirit or scope of the invention; therefore, without limiting myself to the exact construction shown, what I claim is:—

1. In an automatic train-stopping device, the combination with a locomotive having manually-operated power-controlling means, of auxiliary means for shutting off the power independently of said manually-operated means, gravity-controlled devices for operating said shut-off means, a fluid-pressure device for operating the shut-off means positively, a detent-means to prevent the operation of said shut-off means by either of said operating-means, a governor-device operated from a going part of the locomotive, and means actuated by said governor-device to release the detent-means and cause action of the auxiliary shut-off means when the speed of the locomotive exceeds a predetermined limit.

2. In a safety-stop device, the combination with a locomotive having manually-operated power-controlling means, of auxiliary means for shutting off the power independently of said manually-operated means, gravity-controlled means to actuate said auxiliary shut-off means, power-operated means to actuate said auxiliary shut-off means positively, a detent-means for normally maintaining both of said actuating-means inoperative, a governor-device operated from a going part of the engine, and means actuated by said governor-device at a predetermined speed of the engine to release the detent-means.

3. In a safety-stop device, the combination with a locomotive having manually-operated power-controlling means, of auxiliary means for shutting off the power independently of said manually-operated means, gravity-controlled devices for actuating said shut-off means, power-operated devices for actuating said shut-off means positively, a detent-means for preventing the action of both of said actuating-devices for the shut-off means, electrically-operated

devices for releasing the detent-means, a switch for controlling the electrically-operated devices, and a governor-device for operating the switch when the locomotive exceeds a predetermined speed limit.

4. In a device of the class specified, the combination with a locomotive having manually-operated power-controlling means, of auxiliary means for shutting off the power independently of said manually-operated means, gravity-controlled devices for actuating said shut-off means, a separate power-operated device for actuating the shut-off means, a detent-means for maintaining both of said actuating-means normally inoperative, an electro-magnet for releasing said detent-means, an electric circuit connecting said magnet with a source of current, a switch in said circuit, and means controlled by the speed of the locomotive to operate the switch when a predetermined limit is exceeded.

5. In a device of the class specified, the combination with a locomotive having manually-operated power-controlling means, of auxiliary means for shutting off the power independently of said manually-operated means, gravity-controlled devices for actuating said shut-off means, an additional power-operated device for actuating the shut-off means, a detent-means for preventing the operation of both of said actuating-means, an electro-magnet, and means operated from said magnet to release the detent-means and cause the operation of the shut-off actuating-means.

6. In a device of the class specified, the combination with a locomotive having manually-operated power-controlling means, of auxiliary means for shutting off the power independently of said manually-operated means, gravity-controlled devices for operating said shut-off means, a fluid-pressure device for operating said shut-off means positively, a detent-means for normally preventing the operation of the shut-off means, and electrically-controlled devices to release the detent and cause action of the shut-off operating means.

7. In a device of the class specified, the combination with a locomotive having manually-operated power-controlling means, of auxiliary means for shutting off the power independently of said manually-operated means, gravity-controlled devices for operating said auxiliary shut-off means, detent-means for normally preventing the operation of said auxiliary shut-off means, a fluid-pressure cylinder, a piston slidably in said cylinder to operate the auxiliary shut-off means positively, a valve for controlling the pressure on the piston, an electro-magnet, and an armature actuated thereby to release the detent-means and operate the valve.

8. In a device of the class described, the

- combination with a locomotive, of auxiliary means for shutting off the power thereof, gravity-controlled devices for actuating said shut-off means, detent-means for normally maintaining said gravity devices inoperative, a fluid-pressure cylinder, a piston in said cylinder, means connecting said piston to operate the shut-off means, a valve-chamber for controlling the pressure on the piston, a valve slidable in said chamber, an electro-magnet, and an armature operated therefrom to release the detent-means and slide the valve to admit pressure to the cylinder to operate the piston.
- 15 9. In a device of the class specified, the combination with a locomotive, of means for shutting off the power thereof, a fluid-pressure cylinder, a piston slidable therein, means connecting said piston to operate the 20 shut-off means during its downward movement in the cylinder, a valve-chamber having ports communicating with the upper and lower ends of the cylinder, a valve for opening and closing said ports, a normally 25 energized electro-magnet, and an armature connected to the valve and adapted to maintain it in position to admit pressure to the lower end of the cylinder when the magnet is energized and to be operated by gravity 30 when the magnet is deenergized to slide the valve to admit pressure to the upper end of the cylinder.
10. In a device of the class specified, the combination with a locomotive, of gravity-operated means for shutting off the power thereof, a fluid-pressure device for operating said shut-off means positively, a valve for controlling the pressure in said device, an electro-magnet, and an armature adapted to be attracted by the magnet to maintain the valve in position to cause the pressure to normally hold the shut-off means inoperative, and when released to cause the pressure to operate the shut-off means.
- 45 11. In a device of the class specified, the combination with a locomotive, of means for shutting off the power thereof, a fluid-pressure cylinder, a piston in said cylinder connected to operate the shut-off means, means to admit pressure at one end of the cylinder to move the piston to open the shut-off means, means to admit pressure at the opposite end of the cylinder to move the piston to close the shut-off means, a gravity-controlled balanced valve to operate the pressure-means, an electro-magnet, and an armature connected to the valve and adapted to be attracted by the magnet against the influence of gravity.
- 55 60 12. In a device of the class specified, the combination with a locomotive, of means for shutting off the power thereof, a fluid-
- pressure cylinder, a valve-chamber connected therewith, a valve slidable therein, means to admit pressure at two points in the valve-chamber to maintain the valve normally balanced while admitting pressure to the lower end of the cylinder, a piston in the cylinder adapted to be moved by said pressure to open the shut-off means, a normally energized electro-magnet, and an armature connected with the valve to hold the latter against gravity when the magnet is energized and to release the valve to admit pressure to the cylinder to close the shut-off means when the magnet is deenergized.
13. In a device of the class specified, the combination with a locomotive, of means for shutting off the power thereof, a fluid-pressure cylinder, a piston in said cylinder connected to operate the shut-off means, a valve-chamber having ports opening therefrom into each end of the cylinder, a valve slidable in the chamber, means to admit pressure at two points in the valve-chamber to maintain the valve balanced with one port open to hold the piston in position with the shut-off means open, an electro-magnet, and an armature controlled from the magnet to actuate the valve to admit pressure to the cylinder to move the piston to close the shut-off means.
14. In a device of the class specified, the combination with a locomotive having manually-operated power-controlling means, of auxiliary means for shutting off the power independently of said manually-operated means, an electro-magnet for operating said auxiliary shut-off means, a source of electrical energy, a normally-closed main circuit including said magnet and the source of energy, a switch for connecting said circuit with a ground in the locomotive, a branch circuit also connecting said main circuit with a ground in the locomotive, a second switch for interrupting the main circuit when the locomotive is running at a predetermined speed, a switch for normally closing the branch circuit, contact-means for opening the switch in the branch circuit when the locomotive passes into a block, means for completing the branch circuit outside the locomotive including the service rail and a contact rail, and means for interrupting said outside circuit under danger conditions to cause the magnet to operate the shut-off means.
